RAILWAY TRACK CIRCUIT APPARATUS

Frank H. Nicholson, Wilkinsburg, Pa., assignor
to The Union Switch & Signal Company,
Swissvale, Pa., a corporation of Pennsylvania

Application July 25, 1935, Serial No. 33,083

1 Claim. (Cl. 246—34)

My invention relates to railway track circuit apparatus and more specifically to apparatus of the coded type wherein the energy is supplied to the rails in the form of impulses.

5 In coded direct current track circuits it has been found that the track rails resting on the ties and ballast may constitute a form of storage battery which may store energy during the "on" periods of the impulses. This stored energy dis-

10 charges into the code following track relay during the "off" periods of the impulses with the result that the normal operation of the relay is interfered with and in some instances the release of the relay is prevented entirely. One

15 feature of my invention is the provision of means for minimizing the effect of this stored energy on the operation of the code following track relay.

I will describe two forms of apparatus embodying my invention, and will then point out 20 the novel features thereof in the claim.

The accompanying drawing is a diagrammatic view illustrating two forms of apparatus embodying my invention. That is, as hereinafter will be explained more in detail, the control of 25 the coded track circuit current for section 1T embodies one form of my invention and the control of the coded track circuit current for section 2T embodies another form of my invention.

Referring now to the drawing, the reference 30 character X designates a stretch of railway track over which traffic normally moves in the direction indicated by the arrow. The rails 1 and 2 of track X are divided by insulated joints 3 into sections 1T and 2T. Each section 1T and 2T is provided with a code following track relay connected across the rails at the entering end of the section and designated by the reference character TR with a distinguishing prefix, and with a source of direct current designated by the reference 35 character B with a distinguishing prefix, for supplying energy to the rails at the other end of the section.

The battery 1B, in series with a resistor 4, is connected to the rails of section 1T by means of 40 a front point of contact 5 of a current coding relay designated by the reference character C.

The coding relay C is controlled in any convenient and well-known manner, not shown in the drawing, so that front point of contact 5 closes and opens a definite and predetermined 45 number of times per minute in accordance with traffic conditions in advance. For example, if the track section immediately in advance of section 1T is occupied by a train, the relay C may operate 80 times per minute, whereas, if this ad-

vance section is unoccupied, the relay may operate 180 times per minute.

The code following track relay 1TR operates its contact 6 in accordance with the impulses supplied to the rails by relay C and may be employed for controlling a traffic governing device, such as a signal, in accordance with the character of the code received; or, as here shown, may be utilized for controlling the supply of coded current to the track section next in rear. 10

In the latter event, the relay 1TR simply repeats the code supplied by coding relay C, and the sections 1T and 2T are considered to be one block. This arrangement is frequently resorted to for track circuiting a section of track of a 15 length such as to make the operation of a single track circuit impossible or impractical. The current from battery 2B is supplied to the rails of section 2T over the back point of contact 6 of relay 1TR through a resistor 4, and code following track relay 2TR responds to the impulses of current supplied to the rails of section 2T. Thus, relay 1TR responds to the coded current supplied to the rails of section 1T by relay C, and relay 2TR responds to the coded current supplied to the rails of section 2T by relay 1TR. The relay 2TR may be utilized for controlling traffic 20 controlling devices in accordance with the coded current with which it is supplied.

As pointed out previously, I have found that 30 the rails and ballast of a coded track circuit may in some respects be similar to a storage battery. That is, the rails and ballast may receive and store a charge of energy during the "on" periods of the coded current. This stored current is discharged into the code following track relay during the "off" periods with the result that the proper operation of the code following track relay 35 may be interfered with.

I have also discovered that if the rails of the 40 track circuit are shunted by a path of comparatively low resistance during the "off" periods of the coded current, the stored energy in the rails and ballast will be discharged and shunted away from the code following track relays so that these 45 relays are permitted to function properly.

I provide this shunt path across the rails of section 1T in one form by connecting rail 1 to the back point of contact 5 of relay C by means of connection 7, and across the rails of section 2T in another form by connecting rail 1 to the front point of contact 6 of relay 1TR by means of connection 8. It will be obvious that when relay C is deenergized so that the back point of contact 5 is closed, the rails 1 and 2 of section 55

'T will be shunted by connection 7, and that when relay 'TR is energized so that the front point of contact 6 is closed, the rails 1 and 2 of section 2T will be shunted by connection 8. In other words, the rails of each section will be shunted by a path of comparatively low resistance whenever the coded track circuit energy for that section is absent so that any energy stored in the rails and ballast will be dissipated through the low resistance shunt path. Before the coded energy is again supplied to the rails, the shunt paths, of course, will be opened.

Both forms of my invention, therefore, provide simple and reliable means for reducing or minimizing the storage battery effect of coded direct current track circuits so that the code following track relays associated with such track circuits may function properly.

Although I have herein shown and described only two forms of apparatus embodying my invention, it is understood that various changes

and modifications may be made therein within the scope of the appended claim without departing from the spirit and scope of my invention.

Having thus described my invention, what I claim is:

In combination, a first and a second section of railway track, means for supplying coded current to the rails of said first section, a code following track relay for said first section responsive to said coded current, means including a back contact of said track relay for repeating said coded current into said second section, and means including a front contact of said track relay for closing a shunt path across the rails of said second section to thereby discharge the energy stored in the rails and ballast of said second section in order to eliminate distortion of the coded current repeated into said second section.
